CLAIM

The ornamental design for a flag holder bracket for a truck, as shown and described.

DESCRIPTION

FIG. 1 is perspective view of the bracket of the present invention;

FIG. 2 is a front elevation view of the bracket of the present invention;

FIG. 3 is a back elevation view of the bracket of the present invention;

FIG. 4 is a left side elevation view of the bracket of FIGS. 2-3;

FIG. 5 is a right side elevation view of the bracket of FIGS. 2-3;

FIG. 6 is a top plan view of the bracket of FIGS. 2-3; and,

FIG. 7 is a bottom plan view of the bracket of the present invention.
